UNITED STATES PATENT OFFICE.

WELLS R. DAVIS, OF ALBERTA, MISSOURI.

CURRY-COMB.

SPECIFICATION forming part of Letters Patent No. 398,820, dated March 5, 1889.

Application filed November 22, 1888. Serial No. 291,561. (No model.)

To all whom it may concern:

Be it known that I, WELLS R. DAVIS, a citizen of the United States, residing at Alberta, in the county of Henry and State of Missouri, have invented new and useful Improvements in Curry-Combs, of which the following is a specification.

My invention relates to improvements in curry-combs; and it consists in certain novel features, hereinafter described and claimed.

In the accompanying drawings, Figure 1 is a central section of a curry-comb provided with my improvements. Fig. 2 is a perspective view of the cleaning attachment removed, and Fig. 3 is a front view showing the cleaning attachment thrown out in dotted lines.

Referring to the drawings by letter, A designates the curry-comb, of the usual or any preferred construction, having the transverse series of teeth B, as shown. The curry-comb is provided at its corners with the slots C, for a purpose which will be hereinafter set forth.

D designates my improved cleaning attachment, consisting of the side bars, E, having the vertical guide-pins F at their ends, which project upward through the slots C in the corners of the curry-comb, as shown. The said guide-pins are provided with the horizontal shoulders H, which are adapted to contact with the under side of the back of the curry-comb, and thereby limit the upward movement of the cleaning attachment. The guide-pins are further provided at their upper ends with the lateral projections or stops H, which

are adapted to contact with the upper side of the curry-comb, and thereby limit the downward movement of the cleaning attachment. The side bars, E, are further provided at their centers with the standards I, the upper ends

of which are connected by cross-bar J, as shown. A leaf-spring, K, is secured at its center to the upper side of the curry-comb and has its free ends bearing against the under side of the cross-bar J, so as to hold the cleaning attachment normally elevated.

A series of cross-bars, L, are secured between the side bars, E, and are provided with longitudinal slots M, through which the tooth-bars of the curry-comb pass, the walls of the said slots M bearing against the opposite sides of the tooth-bars, as shown in Fig. 1.

In practice the curry-comb is employed in the usual manner to curry a horse, and when the teeth have become full of hair the operator presses upon the cleaning attachment with his thumb, so as to project the same toward the edges of the teeth, thereby quickly removing the hair from the teeth and cleaning the comb. This operation also straightens any teeth which may have been accidentally bent, as the walls of the slots in the cross-bars bear against the opposite sides of the tooth-bars, so that as the said cross-bars are pushed toward the edges of the teeth the bent and crooked teeth will be bent back into their proper shape. Upon releasing the pressure upon the cross-bar J the spring at once returns the cleaning attachment to its normal elevated position, leaving the teeth of the curry-comb free for use. The guide-pins at the corners of the attachment cause the same to move in a true vertical plane, so that twisting of the parts will be effectually prevented. The horizontal shoulders and the lateral projections on the guide-pins are arranged at such points that the attachment will be prevented from being pressed outward beyond the edges of the teeth of the curry-comb, and will also be prevented from being forced against the back of the curry-comb. By this arrangement the attachment is prevented from slipping from the tooth-bars, and also prevented from being broken by contacting with the back of the comb.

The efficiency of my device is obvious, and as it is simple in its construction and does not materially add to the weight or size of the curry-comb, nor interfere with the use of the same in any way, its advantages are thought to be readily appreciable.

Having thus described my invention, I claim—

1. The combination, with the curry-comb having the slots C at its corners, of the cleaning-frame having the guide-pins at its corners projecting through said slots and a spring secured to the comb and acting on the cleaning-frame to hold it normally withdrawn, as set forth.

2. The combination, with the curry-comb having stationary teeth and provided with the slots C at its corners, of the cleaning-frame

having a series of longitudinally-slotted bars fitting snugly upon the teeth of the comb, and provided at its corners with guide-pins projecting through the slots C, and a spring to hold the cleaning-frame normally withdrawn, as set forth.

3. The combination, with the curry-comb having slots C at its corners, of the side bars, E, the guide-pins erected on said side bars at 10 the ends of the same and extending through the said slots C, and provided with the shoulders H and the projections H', adapted to contact with the opposite sides of the curry-comb,

the cross-bars secured to the side bars, E, and fitting upon the teeth-bars of the curry-comb, 15 the standards erected on the side bars, the cross-bar extending between said standards, and the spring secured on the curry-comb and bearing against said cross-bar, as set forth.

In testimony that I claim the foregoing as 20 my own I have hereto affixed my signature in presence of two witnesses.

WELLS R. DAVIS.
